UNITED STATES PATENT OFFICE.

JOSEPH ODORIZZI, OF TRINIDAD, COLORADO, ASSIGNOR TO THE FORBES MINE CAR APPLIANCE COMPANY, OF SAME PLACE.

DUMP-CAR.

SPECIFICATION forming part of Letters Patent No. 481,811, dated August 30, 1892.

Application filed January 11, 1892. Serial No. 417,757. (No model.)

To all whom it may concern:

Be it known that I, JOSEPH ODORIZZI, of Trinidad, in the county of Las Animas and State of Colorado, have invented a new and 5 useful Improvement in Dump-Cars, of which the following is a specification.

My invention relates to dump-cars used in mines, &c., for transporting ore, coal, &c. It has more especial reference to the means for 10 locking the suspended end door of the car; and it consists in the peculiar construction and arrangement of these devices, as will be hereinafter fully described.

Figure 1 is an end elevation of the car-door, 15 and Fig. 2 is a vertical longitudinal section of the same, taken on line *x x*.

A represents the car-body, which is made of metal or other suitable material; and B is the end door of the car, which door is at- 20 tached to and suspended from a rod *b*, connected to its upper horizontal edge and journaled in bearings in the sides of the car. To the door B near its lower edge is jointed or fulcrumed a T-shaped lever-latch com- 25 posed of a horizontal portion *c*, a vertical downwardly-projecting bolt portion *c'*, and a right-angular offsetting handle portion *c''*, which is formed on the end of the horizontal section opposite its fulcrum and constitutes 30 a handle for operating the latch.

D is the draw-bar of the car, which is se- 35 cured to its bottom, and outside the plane of the door is provided with a stout bevel-faced lug or projection *d*.

E is a flat spring riveted to the door oppo- 40 site the handle of the latch and bearing out- wardly with a frictional contact against the horizontal portion of the latch to hold it against accidentally jarring out of position.

F is a stop pin, lug, or bolt fastened to the 45 end door beneath the horizontal portion of the latch and supporting the same in its nor- mal position, with the pendent vertical bolt portion *c'* directly in line with the draw-bar

and immediately behind the retaining-lug *d* of the draw-bar. When the parts are in the

position last described, it will be seen that the vertical portion *c'* of the latch lies be- 5 hind the lug *d*, and by preventing the door from being pushed outwardly securely retains the contents of the car, the spring *E* serving to hold the latch to its position, so that the vertical bolt portion *c'* does not jolt out of the plane of the lug *d* in one direction and the stop *F* holding it against movement in 55 the other. When the door is to be opened, however, the handle portion *c''* of the latch is grasped and raised or struck and raised and the friction of the spring being overcome, the latch is deflected and the vertical bolt por- 60 tion *c'* of the latch is moved to one side of the locking-lug *d*, as shown in dotted lines, which permits the door to come open. In- stead of locating the lug *d* on the draw-bar any catch or projection on the bottom of the 65 car may be used.

Having thus described my invention, what I claim as new is—

1. The combination, with a dump-car hav- 70 ing a draw-bar and a catch or lug *d*, of a sus- pended end door having a latch connected with a horizontal portion fulcrumed to the door and a vertical portion extending down- wardly to engagement with said lug *d*, and a stop for maintaining the normal locking po- 75 sition of said latch, substantially as shown and described.

2. The combination, with a dump-car hav- 80 ing a draw-bar and a catch or lug *d*, of a sus- pended end door having a latch constructed with a horizontal portion fulcrumed to the door, a vertical portion extending downwardly to engagement with said lug *d* and an offset- 85 ting handle, a stop for maintaining the nor- mal locking position of the latch, and a re- taining-spring for holding the latch against jolting loose, substantially as shown and de- scribed.

JOSEPH ODORIZZI.
